UNITED STATES PATENT OFFICE.

RICHARD WILLIAM GALLAGHER, OF SAN FRANCISCO, CALIFORNIA,
ASSIGNOR TO AUTOMATIC METER CO., OF SAN FRANCISCO, CALI-
FORNIA.

BILL-DELIVERY MECHANISM FOR METERS.

No. 823,773.

Specification of Letters Patent.

Patented June 19, 1906.

Application filed May 19, 1904. Serial No. 208,670.

To all whom it may concern:

Be it known that I, RICHARD WILLIAM GALLAGHER, a citizen of the United States, residing at San Francisco, in the county of San Francisco and State of California, have invented certain new and useful Improvements in Bill-Delivery Mechanism for Meters, of which the following is a specification.

My invention relates to an improved device for automatically delivering bills of meters—such as gas-meters, electrical meters, water-meters, and the like—the object of my invention being to provide a device by means of which the consumer can at any time obtain a record of the amount measured by the meter.

This device will also prove of value for use by inspectors of gas-meters or electric meters, who, instead of reading the meter, will take a duplicate record of the same, one of which will be presented to the consumer as a bill and the other will be turned in at the office. A third record will be retained in the meter as a check upon the bill-collector.

My invention, therefore, resides in the novel construction, combination, and arrangement of parts for the above ends hereinafter fully specified, and particularly pointed out in the claims.

In the accompanying drawings, Figure 1 is a vertical section of my improved apparatus. Fig. 2 is a front view of the apparatus, the casing being removed. Fig. 3 is a vertical section of the lower portion of the apparatus in the position in which the lever is depressed. Fig. 4 is a horizontal section on the line A A of Fig. 1. Fig. 5 is a front view of the apparatus. Fig. 6 is a bottom plan view of the recording-plate.

Referring to the drawings, 1 represents a suitable casing having a door 2 at the front hinged at its upper edge, as shown at 3. Said door has a vertical slot 4 extending centrally thereof, and through said slot extends an operating-lever 5, having a head 6, by which the lever may be vibrated. The lower end of said slot is enlarged, as shown at 7, to such size as to permit the head 6 to pass therethrough, so that when the lever has been depressed to its lowest position and the head is opposite to said slot the door can be swung upward, permitting access to the interior of

the casing; but said door cannot be opened until said lever has first been brought to its lowest position. The importance of this feature will appear in the further description of the device. Said lever at its rear end is yoke-shaped and is pivoted at 8 at the back of the machine, being retracted by springs 9 and the sides of the yoke having slots 10, through which pass the trunnions 11 of a recording-frame 12. Said frame is oblong in form and has a transverse portion 13, in which is mounted the shaft 14 of recording-wheels 15. At its corners said frame carries vertical guiding-sleeves 16, which slide upon vertical guide-rods 17, secured between an upper horizontal plate 18 and a lower horizontal plate 19. Upon the lower ends of said sleeves is secured a recording-plate 20. The recording is preferably effected by means of needle-points 21, secured on the under side of the plate 20, which are arranged on the plate in the form of letters or other index character and perforate the paper to make the desired record. In like manner the recording-wheels print by perforating paper, with needle-points secured upon their peripheries, in the form of figures. The under side of the recording-plate is on the same level with the bottom of the recording-wheels. The meters are identified by numbers 51 on the recording-plates. By depressing the lever 5 said wheels and plate are brought down, so as to simultaneously perforate three sheets of paper. These sheets pass from rolls of paper 22, the shafts of which are received in spring-clamps 23, secured on the under side of the horizontal plate 19, a door 24 being provided in the bottom of the casing for placing said rolls in position, with their shafts in said clamps. The three sheets of paper pass over a pad 25, of rubber or other suitable material, supported by said plate 19, which is slotted at the end, as shown at 26, to permit said sheets of paper to pass to the upper side thereof. Said sheets pass between feed-rollers 27 28, of which the upper two, 27, are revolved by pressure from the lower roller 28, while said lower roller is revolved by pinions 29, secured thereto, meshing with gear-wheels 30, which are loose on the shaft 31 of a winding-up roller 32. Said shaft 31 is revolved intermittently upon the

return or upward motion of the lever by the following construction. To the slotted sides of the yoke are pivotally attached links 33, which are pivoted at their lower ends to lever 34, which revolve loosely upon the shaft 31 of the winding-up roller and carry at their opposite ends pivoted pawls 35, drawn inward by springs 36 to engage ratchet-wheels 37, attached, respectively, to the gear-wheels 30. When the lever 5 descends, the links 33 cause the pawls 35 to travel over the ratchet-wheels 37, and upon the return motion of the lever said pawls engage said ratchet-wheels and revolve the same, and therefore also the gear-wheels 30 and rollers 27 28, advancing the sheets of paper. Two of the sheets of paper pass out through a slot 38, while the lowest sheet passes to the winding-roller 32, being wound up thereon by springs 39 on the shaft 31.

The three recording-wheels have secured thereto gear-wheels 40, which when brought to their upper position mesh with three gear-wheels 41 42 43. The gear-wheel 41 is connected by a train of gearing 44 with a shaft 45, coming from the gas or other meter. The gear-wheel 41 is on the same shaft with a pinion 46, meshing with the gear-wheel 42, the latter being of ten times the diameter of the pinion 46, and the gear-wheel 42 in like manner is on the same shaft with a pinion 47, meshing with the gear-wheel 43 of ten times its diameter. The gear-wheels 41 42 43 thus represent the thousands, tens of thousands, and hundreds of thousands of cubic feet of gas measured by the meter. It is now, however, no longer necessary to provide the usual dial-plate, as the meter is no longer read from the dials, but a record is taken therefrom. These dials may, however, be retained, if desired, as they form a check on the recording device.

The door 2 is locked by a padlock 48 and staple 49 or other suitable lock.

The strips of paper to furnish the bills are previously printed or stamped with numbers 51, which will correspond to the numbers of the bills.

The operation of the device is as follows: The gas-bill collector pulls down the lever 5, which causes the recording frame and wheels to descend until the needles thereon perforate the three sheets of paper which lie on the top of the rubber pad. When the lever 5 rises again under the action of springs 9, the needle-points are withdrawn from the sheets of paper and the pawls engage the ratchet-teeth and revolve the feed-rollers, causing the sheets of paper to advance between said rollers. When the recording-wheels return to their original position, they will again mesh with the gear-wheels 41 42 43 either immediately or before said gear-wheels have advanced through the distance of one tooth.

The two sheets which project are torn off by the gas-bill collector and are handed to the consumer, and if the bill is at that time paid the two sheets are both suitably stamped or perforated, as with the word "Paid," and one of them is handed to the consumer and the other is turned in at the office, together with the amount collected. If the bill is not paid, one of the sheets is left with the consumer and the other is turned in at the office, showing that the bill is not paid. The gas-collector will now unlock the door and will by hand turn back the counting-wheels to zero and then after locking the door will take a second impression and hand a second slip to the consumer, showing that the indicator now stands at zero and in like manner, as before, turning in a duplicate of the same at the office.

It will be observed that by reason of the fact that the casing cannot be opened until an impression has been made a safeguard is provided against the bill-collector first opening the box, then advancing the recording-wheels by hand, and then taking an impression which he can present to the consumer, for the third sheet will record that an impression has been made after the original impression taken when the counting-wheels were at zero and before that presented to the consumer and showing that the device has been tampered with. At all times the consumer can take a record of gas or other commodity supplied consumed up to that time. For the reason that the bills are numbered in consecutive order the consumer will be able to detect at once should any unauthorized person or the bill-collector take a record without his knowledge. After the strip showing the recording-wheels at zero has been handed to the consumer and the bill-collector has departed the consumer can himself go and take another record, showing that the counting-wheels are at zero.

This system reduces the amount of book-keeping required and also reduces the force required to collect the bills, as the bills can be presented by the same person who takes the record of the consumption of gas or other commodity. On account of the bill being immediately presented and paid in the majority of cases an expensive bookkeeping staff is not required.

Various modifications of the system may be adopted. For instance, the head of the lever may be removable and may be carried about by the employee or persons supplying the gas or other commodity, or, if desired, the head or key may be retained in the possession of the consumer, so that only upon calling upon the consumer for the same and therefore in his presence, if required, can the bill-collector make the record and take the bill; or, if desired, the bill-collector and the

consumer may each be provided with a separate head or key.

I claim—

1. In an apparatus of the character described, the combination with a set of counting-wheels, of recording-wheels, a lever carrying the same, said recording-wheels being adapted to be moved onto recording-sheets to record the numbers thereof, said recording-wheels in their normal position meshing with said counting-wheels, and means for advancing said recording-sheets, automatically operated by the movement of said lever, substantially as described.
2. In an apparatus of the character described, the combination of a set of counting-wheels, recording-wheels normally meshing with said counting-wheels, a lever carrying said recording-wheels, said recording-wheels being adapted to be moved onto recording-sheets by said lever, and means automatically operated upon the return movement of the lever for advancing said recording-sheets, substantially as described.
3. In an apparatus of the character described, the combination of counting-wheels, recording-wheels having on their peripheries needle-points in the form of figures and having gear-wheels meshing with said counting-wheels, a shaft upon which said recording-wheels revolve, a frame carrying said shaft, and means for moving said frame, said recording-wheels being adapted to be moved onto recording-sheets by the movement of said frame, substantially as described.
4. In an apparatus of the character described, the combination of counting-wheels, recording-wheels having on their peripheries needle-points in the form of figures and having gear-wheels meshing with said counting-wheels, a shaft upon which said recording-wheels revolve, a frame carrying said shaft, a plate surrounding the lower portions of said recording-wheels and likewise having on its under side needle-points in the form of letters or characters, and means for moving said frame and plate, said recording-wheels and plate being adapted to be moved onto recording-sheets, substantially as described.
5. In an apparatus of the character described, the combination of counting-wheels, recording-wheels having gear-wheels meshing with said counting-wheels, a shaft upon which said recording-wheels revolve, a frame carrying said shaft, means for moving said frame, said recording-wheels being adapted to be moved onto recording-sheets by the movement of said frame, and means for taking an impression from said wheels on said sheets, substantially as described.
6. In an apparatus of the character described, the combination of counting-wheels, recording-wheels having gear-wheels meshing with said counting-wheels, a shaft on

which said recording-wheels revolve, a frame carrying said shaft, a plate surrounding the lower portion of said recording-wheels, means for moving said wheels and plate onto recording-sheets and means for taking an impression therefrom onto said sheets, substantially as described.

7. In an apparatus of the character described, the combination of counting-wheels, a frame carrying a shaft and a recording-plate, recording-wheels on said shaft having gear-wheels arranged in their normal position to mesh with the counting-wheels, said recording-plate and wheels being provided with means for making an impression, guides for said frame guiding its movement to and from the counting-wheels, a lever engaging said frame to move it to recording-sheets, and springs for retracting the lever and frame, substantially as described.

8. In an apparatus of the character described, the combination of counting-wheels, a frame carrying a shaft and a recording-plate, recording-wheels on said shaft having gear-wheels arranged in their normal position to mesh with the counting-wheels, said recording-plate and wheels being provided with means for making an impression, guides for said frame guiding its movement to and from the counting-wheels, a lever engaging said frame to move it to recording-sheets, springs for retracting the lever and frame and means automatically operated by the movement of the lever for advancing the sheets, substantially as described.

9. The combination of a casing, counting-wheels, recording-wheels arranged in their normal position to be actuated by said counting-wheels, a frame carrying said recording-wheels, a lever for moving said frame, said lever being accessible from the outside of the casing, the recording-wheels being adapted to be moved onto recording-sheets by said lever, and a door or closure for said casing prevented from being opened by said lever except when it has been brought to a position to make an impression from the recording-wheels on the recording-sheets, substantially as described.

10. In an apparatus of the character described, the combination of three gear-wheels on separate shafts, the second engaged by a pinion on the same shaft as the first and third by a pinion on the same shaft as the second, three recording-wheels all on the same shaft and severally in mesh with the respective gear-wheels, and means for taking an impression on recording-sheets from said recording-wheels, substantially as described.

11. In an apparatus of the character described, the combination of three gear-wheels, the second engaged by a pinion on the same shaft as the first and the third by a pinion on the same shaft as the second, three recording-

wheels all on the same shaft and respectively operated by the gear-wheels, means for taking an impression on recording-sheets from said recording-wheels, and means for advancing 5 said recording-sheets, operated by the return movement of taking the impression, substantially as described.

In witness whereof I have hereunto set my hand in the presence of two subscribing witnesses.

RICHARD WILLIAM GALLAGHER.
